UNITED STATES PATENT OFFICE.

CHARLES ASA TAYLOR, OF CHICAGO, ILLINOIS.

IMPROVEMENT IN TRUNKS.

Specification forming part of Letters Patent No. 128,925, dated July 9, 1872

SPECIFICATION.

To all whom it may concern:

Be it known that I, CHARLES ASA TAYLOR, of Chicago, in the county of Cook and State of Illinois, have invented certain Improvements in Trunks, of which the following is a specification, reference being had to the accompanying drawing.

My invention consists in a yielding roller of novel construction, to be applied entirely on the outside of the trunk; in spring-catches to hold the trunk shut; in a brace of peculiar construction to be applied to the outside of the body for the purpose of holding up the top or lid; and in a spring-arm for supporting the tray when it is turned up.

Figure 1 is a perspective view of my trunk with the lid and the tray turned up; Fig. 2, an end view of the tray, showing the brace for supporting its cover; Fig. 3, a vertical section of one end of the tray with the cover raised, showing the manner in which the supporting-brace locks on the edge; Fig. 4, a vertical section through one of the clasps or fastenings; and Fig. 5, a vertical section through one of the rollers.

In constructing my trunk I build its body in the ordinary manner and provide it with the usual hinged-top B and tray C, as shown. Instead of attaching the rollers D rigidly to the bottom, in the usual manner, I mount them in the ends of spring-arms E, which I secure to the bottom of the trunk, as shown. Over each spring and its roller I secure a metal plate or socket, F, provided with an opening for the roller to extend out through, as shown, the plate or socket being extended up on the end of the trunk, as shown, so that it has a strong hold and cannot be torn loose, and so also that it forms an angle-iron to strengthen the body. The springs are made of sufficient strength to hold the rollers out and support the trunk when filled, but when the trunk is thrown violently down the springs yield and allow the rollers to fall back into the sockets or plates F, so that the blow is received upon the solid metal. When the rollers are out in position they are held or supported by the sockets so that they cannot be wrenched off sidewise by pulling the trunk about. By thus mounting the rollers on the springs and protecting them by the sockets they are guarded from violent blows, and from lateral strain, so

that there is no danger of their being knocked off or injured by any rough usage to which the trunk may be subjected. The spring-roller and its socket, constructed as described, can be applied directly to the outside of an ordinary trunk without cutting the trunk or stopping to fit the socket thereto. In order to strengthen the top of the trunk, and prevent it from being broken when the trunk is thrown violently about, I apply to each corner a heavy metal corner piece or knob, H, provided with three flat arms which are securely riveted to the top, end, and front, respectively, as shown in Fig. 1. These corner pieces may be made of either cast or wrought metal, but should, in either case, be made of such strength and thickness that they cannot be bent or broken by any blows to which they may be subjected. The corner pieces thus constructed and applied serve to strengthen and protect the corners of the top so that they cannot possibly be broken or injured by throwing the trunk about. Instead of providing the top of the trunk with the usual straps for fastening it down I attach to its front two spring-catches, I, and to the top two tangs or plates, J, which lock into and are held by the catches. Each catch consists of a metal socket, e, provided with a hinged latch or hook, f, and with a flat spring, g, which bears against the lower end of the latch and keeps its upper end pressed inward against the socket. The upper end of the latch or hook is provided with a prong, i, which extends through into the socket, as shown in Fig. 4, the upper side of the prong being beveled off, as shown. The tangs on the top or lid are provided with beveled ends and with holes or openings, as shown. When the top is pressed down the tangs slide down into the sockets, and the prongs i of the latches lock through them, in the manner shown in Fig. 4, so as to hold the top or lid down securely. In order to unlock latches it is only necessary to turn back the upper ends of the hooks or latches so as to draw the prongs out of the tangs. After the latches are turned back a certain distance the springs hold them in position, as shown in Fig. 1, and in dotted lines in Fig. 4, so that it is only necessary to attend to one of them at a time.

For the purpose of automatically bracing up the lid or cover, when it is raised, I secure to

the end of the body a plate, L, provided with a horizontal slot having a notch or recess, o, at its back end, and to the lid or top pivot an arm, M, having its lower end provided with a stud, p, which is arranged to work in the slot of the plate, as shown, the body of the plate being set out from the trunk so that the arm fits down inside of it, as shown.

When the top is raised it draws the brace back so that the stud p falls into the notch o and holds it firmly in place, so as to prevent the top from falling. The top is released by simply lifting the end of the brace out of the notch. When the top is closed down the brace shuts down inside of the plate L, which protects the brace from being broken or torn loose, while, on the other hand, the brace prevents the plate from being bent inward or broken when the trunk is thrown down on end or others thrown upon it.

For the purpose of supporting the tray when it is turned up, I secure rigidly to the inside of the body, at one end, an upright spring-arm, P, and to the end of the tray attach a plate, Q, having an inclined stud or projection on its face, so that when the tray is raised the projection slips under and catches behind the arm, as shown in Fig. 1, so as to hold the tray in position. The tray is released when desired by pulling the arm outward sufficiently to clear the projection on the plate.

In constructing my trunk I also extend the sheet-metal binding *i*, commonly used on the corners, from three to ten inches outward on

the body, which is greatly strengthened thereby.

By my various improvements I produce, at a slight increase in cost, a trunk which is much stronger and otherwise superior to those now in use.

Having thus described my invention, what I claim is—

1. The yielding roller for trunks, consisting of the socket having the flat spring mounted therein and provided with the roller in its end, when constructed and arranged as described, so that it may be applied entirely to the outside of a trunk, as set forth.
2. The offset slotted plate L applied to the outside of the body, in combination with the locking-brace M pivoted to the top, and arranged to fold down inside of the plate, as described.
3. The spring-catches I, constructed and applied to the front of the body, as described, in combination with the tongues or hasps J, on the top, when arranged to operate as set forth.
4. The spring-arm P, secured to the end of the body, in combination with the plate or catch Q on the tray, when arranged as described, for the purpose of holding the tray up.

CHARLES ASA TAYLOR.
